UNITED STATES PATENT OFFICE.

WILLIAM HEYSER, OF BALTIMORE, MARYLAND.

OYSTER-PAIL.

No. 892,725.

Specification of Letters Patent.

Patented July 7, 1908.

Application filed November 30, 1907. Serial No. 404,623.

To all whom it may concern:

Be it known that I, WILLIAM HEYSER, of the city of Baltimore and State of Maryland, have invented certain Improvements in Oyster-Pails, of which the following is a specification.

This invention relates to certain improvements in the refrigerator oyster pail shown and described in Letters Patent No. 836,499, granted to me on the 20th day of November 1906, to which reference should be made.

The present invention as hereinafter described, is for the purpose of making the patented pail available when pails of large size are employed, and where the insertion of the ice chamber into a deep body of oysters which offers considerable resistance to such insertion, would result in the injury to the oysters; and it makes it possible to fill the pail with oysters after the application of the ice chamber to the pail, and if preferred, after the said chamber has been supplied with ice.

In the description of the said invention which follows, reference is made to the accompanying drawing forming a part hereof and in which,

Figure 1 is a vertical section of the improved refrigerator pail, and Fig. 2 a top view of the pail with the lid thereof removed.

Referring now to the drawing, 1 represents the wood pail or bucket, and 2 the lid thereof.

3 is the sheet-metal ice chamber shown as rectangular in cross section. The ice chamber 3 is provided with a flange *a* which serves as a cover for the oysters which are contained in the pail exteriorly of the ice chamber, and its edge or circumference which is offset, rests on the shoulder *b* of the bucket. The lid 2 is ultimately fastened by the bar *c* which is hinged at one end to the pail and at the other end held in place by a staple *e*, over which it passes, and a latch *f*.

5, 5 are pins, preferably four in number, secured to the inner surface of the pail near its upper edge, with their ends extending

through holes in the flange *a*. The pins 5 have each a small laterally extending hole *g* through which the securing wire 7 is inserted as in the patented invention. After the attachment of the wire 7 to the pins 5, its ends are connected by an ordinary lead seal 9 to prevent access to the oysters during shipment.

Adjacent to one of the pins 5 the flange of the ice chamber is provided with a filling aperture 10 through which the oysters are poured into the pail; and 12 is a hinged lid adapted to cover the said aperture.

To provide for fastening the lid 12 when closed, and by the same appliances as are used to secure the ice chamber in place, the lid 12, or an extension *h* thereof, is perforated so as to fit over the adjacent pin 5, and in consequence, the wire 7 not only prevents the unauthorized removal of the ice chamber, but renders access to the oysters by way of the aperture 10 impossible without cutting the wire, or tampering with the seal 9.

From the foregoing description it will appear that the ice chamber is placed in the pail before the oysters which are poured into the pail through the aperture 10.

I claim as my invention:—

In an oyster pail having an ice chamber 75 with a flange which serves as a cover for the oysters in the pail, the said chamber being prevented from unauthorized removal by means of perforated pins attached to the pail underneath the flange of the ice chamber, 80 and which extend through the flange, and a wire which is passed through the perforated pins and has its ends secured together, the said flange of the ice chamber having a filling aperture and a hinged lid for the same, which 85 lid is perforated to fit over one of the said pins and is secured by the said wire, substantially as, and for the purpose specified.

WILLIAM HEYSER.
